GLASS CUTTING MACHINE

Harmon W. Archer, Fort Smith, Ark.

Application March 3, 1939, Serial No. 259,699

1 Claim. (Cl. 33—32)

This invention aims to provide a simple but efficient device for cutting glass, novel means being provided for securing the necessary adjustments, to enable the cutter to cooperate properly with the work, and to regulate the width of the strip that is severed.

It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawings:

Fig. 1 shows in plan, a device constructed in accordance with the invention;

Fig. 2 is a longitudinal section on the line 2—2 of Fig. 1;

Fig. 3 is a transverse section on the line 3—3 of Fig. 1;

Fig. 4 is an elevation showing the mechanism whereon the cutting member is mounted, the parts being in the positions which they will assume when the cutter is in operative relation to the glass;

Fig. 5 is a section showing the cutting mechanism raised to an inoperative position;

Fig. 6 is a transverse section showing the latch mechanism in the position of Fig. 4;

Fig. 7 is a transverse section showing the latch mechanism in the position of Fig. 5;

Fig. 8 is a section showing the means whereby the cutter is held in place on the part which carries it.

In carrying out the invention, there is provided a base 1, adapted to support the plate 2 of glass which is to be cut. Standards 3 are secured to the base 1, and in the standards are secured the ends of parallel tracks 4, which may be tubular if desired.

Riders 5 are mounted for reciprocation on the tracks 4. In oppositely disposed riders 5, a scale rod 6 is mounted for longitudinal adjustment, but when the scale rods have been adjusted endwise, they are held in place by set screws 7 threaded into the riders 5.

Carriages 8 are mounted to move along the tracks 4. The carriage 8 is a composite struc-

ture, including a base 9, to which a cap 10 is attached by securing elements 11. In the base 9 of the carriage 8 is secured a bushing 12, of copper or the like, adapted to promote an accurate movement of the carriage along the track 4, the bushing conforming to the track 4. In the cap 10, a peripherally grooved wheel 14 is journaled, on a shaft 15, carried by the cap, the wheel 14 conforming to the track 4.

A support or rod 16 is mounted for endwise adjustment in the caps 10 of the carriages 8, and is held in adjusted positions by set screws 18, threaded into the caps 10. Any suitable means may be provided for securing a reciprocation of the carriages 8 and the support 16 along the tracks 4. If the parts referred to are to be operated by hand, the support 16 may be supplied with a grip 17, capable of being adjusted lengthwise of the support, and held in adjusted positions by a set screw 50.

Loop-shaped slides 19 are adjustable lengthwise of the support 16, and are held in adjusted positions by set screws 20, threaded into the slides. Sockets 21 are rigidly secured to the slides 19, and the axes of the sockets are at right angles 25 to the base 1. Plungers 22 are mounted for endwise sliding adjustment in the sockets 21, the plungers being splined at 23 into the sockets, so that the plungers cannot rotate.

Abutment collars 24 are threaded on the plungers 22, for adjustment, and are held in adjusted position by set screws 25, threaded into the collars. Compression springs 26 are interposed between the abutment collars 24 and the sockets 21. By changing the positions of the collars 24, the compressive effort of the springs 26 may be varied. Stop collars 27 are threaded on the plungers 22, for adjustment, and are held in adjusted positions by set screws 28, threaded into the collars.

Guide pins 29 have their inner ends mounted in the sockets 21. On the guide pins 29, latch rings 30 are slidable, lengthwise of the guide pins. Compression springs 31 surround the guide pins 29, and, cooperating with the sockets 21, tend to move the latch rings 30 to the right in Figs. 6 and 7. Inwardly projecting bolts 32 are secured to the latch rings 30 and are mounted for sliding movement in the sockets 21. The inner ends of 50 the latch bolts 32 are adapted to be received in seats 34 formed in the plungers 22. The latch rings 30 may be shifted, against the action of the return springs 31, to disengage the inner ends of the latch bolts 32 from the seats 34, the latch 55

rings 30 being supplied with outstanding finger pieces 33, for that purpose.

In that end of each plunger 22 which is adjacent to the base 1, there is formed a T-shaped slot 35, extended entirely through the plunger 22. Into the slot 35, may be slipped crosswise, the T-shaped shank 36 of a disk-like foot 37, whereon a cutter 38 is mounted for rotation. Owing to the T-shape of the slot 35, and the corresponding shape of the shank 36, the cutter 38 cannot turn about the axis of the plunger 22 and the cutter 38 always will track properly along the plate 2 of glass. In order to prevent the shank 36 of the cutter-carrying foot 37 from sliding crosswise out of the slot 35, a collar 39 is slidably mounted on the plunger 22 and may be slid down, into engagement with the foot 37, to assume the position delineated in Fig. 8 of the drawings.

20 The scale rods 6 can be adjusted lengthwise in the riders 5 and be held in adjusted positions by the set screws 7. The scale rods 6 and the riders 5 may be moved lengthwise of the track 4 and the mechanism shown in Fig. 4 can be shifted lengthwise of the support 16, the cutters 38 being placed according to the graduations on the scale rods 6, to regulate the width of the strip of glass which is to be cut. By means of the grip 17 or any other appropriate instrumentality, the carriages 25 8 and the support 16 may be slid lengthwise of the tracks 4, the cutters 38 cooperating with the plate 2 of glass, to cut off one or more strips of glass, of different widths.

25 The springs 26 urge the cutters 38 to the glass 30. In the event that there is no plate of glass on the base 1, the movement of the plungers 22 is

stopped by engagement between the collars 27 and the sockets 21.

In the event that it is desired to hold the cutters 38 in spaced relation to the base 1, the latch collars 30 may be moved transversely of 5 the sockets 21, by means of the handles 33, the latch bolts being engaged with the seats 34 of the plungers 22, after the plungers have been raised from the position of Fig. 4 to the position of Fig. 5. 10

The device is simple in construction, but will be found thoroughly advantageous for the ends in view, it being possible to bring about an accurate cutting of a plate of glass, to such dimensions as occasion may require. 15

What is claimed is:

In a machine for cutting glass plate, a base, tracks carried by the base, carriages mounted to move longitudinally of the tracks, a support extended between the carriages and disposed transversely of the tracks, a glass cutter; positioning means for the glass cutter, embodying riders mounted to move along the tracks, and a calibrated rod disposed transversely of the tracks and carried by the riders; and means for mounting the glass cutter for adjustment longitudinally of the support, whereby the working position of the cutter may be determined by reference to the calibrations of the rod, when the positioning means is moved to a place adjacent to the support, the positioning means being movable to a place remote from the support, and then constituting a stop which, forming an abutment for the mounting means, limits the stroke of the cutter with respect to the glass plate to be cut. 20 25 30 35
